DESIGN FOR A GLOBE FOR LIGHTING FIXTURES

John Canice Dunn, Port Jervis, and Max Klein, Brooklyn, N. Y., assignors to Gillinder Brothers, Inc., Port Jervis, N. Y., a corporation of New York

Application December 30, 1935, Serial No. 60,346

Term of patent 3½ years

To all whom it may concern:

Be it known that we, John Canice Dunn, a citizen of the United States and a resident of Port Jervis, in the county of Orange and State of New York, and Max Klein, a citizen of the United States and a resident of Brooklyn, in the county of Kings and State of New York, have invented a new, original, and ornamental Design for a Globe for Lighting Fixtures, of which the following is a specification, reference being had

to the accompanying drawing forming a part thereof.

Fig. 1 is a side elevational view of the globe for lighting fixtures showing my new design; and Fig. 2 is an inverted plan view of the same.

We claim:

The ornamental design for a globe for lighting fixtures substantially as shown.

JOHN CANICE DUNN.
MAX KLEIN.
